UNITED STATES PATENT OFFICE.

ELEAZER KEMPSHALL, OF BOSTON, MASSACHUSETTS, ASSIGNOR TO THE KEMPSHALL MANUFACTURING COMPANY, A CORPORATION OF NEW JERSEY.

MANUFACTURE OF PLAYING-BALLS.

SPECIFICATION forming part of Letters Patent No. 700,659, dated May 20, 1902.

Application filed March 27, 1902. Serial No. 100,226. (No model.)

To all whom it may concern:

Be it known that I, ELEAZER KEMPSHALL, a citizen of the United States, residing in Boston, in the county of Suffolk and State of Massachusetts, have invented certain new and useful Improvements in the Manufacture of Playing-Balls, of which the following is a specification.

This invention relates to the manufacture of playing-balls; and it consists, substantially, in the improvements hereinafter more particularly described.

The invention has reference more especially to golf and similar playing balls, though applicable to the construction of balls employed in games of other kinds; and one of the objects of the invention is to provide a ball of this character which may be propelled a long distance under a powerful impulse, as when struck by a stick or implement in the hands of the operator, but which will not be highly active under a comparatively light blow or impulse.

A further object is to provide a playing-ball of the character referred to which is of maximum integrity and strength.

Figure 1 is a part sectional view of a playing-ball, illustrating my invention; and Figs. 2 to 5, inclusive, are part sectional views in detail, representing the successive steps of application of the alternating spherical laminæ of celluloid or analogous material and a suitable fibrous material, there being an omission of views intermediate the third and final steps of such application. Fig. 6 is a sectional view indicating one means which may be employed to complete the ball after application of the final lamina of the outer shell thereof.

In constructing or manufacturing my improved playing-ball I employ therefor a solid core or filling of any suitable material of preferably a flexible and elastic character, such as india-rubber or gutta-percha, which core is also preferably spherical in form and of comparatively large dimensions proportionate to the diameter of the completed ball. The structure of the ball is completed by an outer shell comprising alternating spherical laminæ of a hard resistant substance, such

as celluloid and fibrous material, the latter preferably consisting of textile fabric of open mesh. In the present case I first render celluloid or other analogous substance soft or plastic, so as to be capable of being taken up by an ordinary brush or dauber, for instance, and I apply directly to the surface of the core or filling of the ball a sufficiently-thick lamina of such substance, which is seasoned or allowed to partially harden, whereupon I then apply to said lamina a lamina of fibrous material in any suitable way. Upon the said lamina of fibrous material I now apply another celluloid lamina in the same way as the first, then onto this second celluloid lamina another lamina of fibrous material, and so on for any desired number of the said alternating laminæ according to the predetermined depth or thickness of the outer shell of the ball. Finally and as thus constructed I place the ball between heated finishing-dies and subject the same to pressure, whereupon the interstices or pores of the fibrous laminæ become filled up by penetration of the material of the celluloid laminæ, and thus is a ball provided the material of the outer shell of which is practically homogeneous and which may be said to comprise concentric spherical strata of intersecting veins formed by the textile or other fibers. This construction of shell has been found to possess integrity and strength and is advantageous for the reasons already furnished.

Specific reference being had to the accompanying drawings by the designating characters marked thereon, A represents my present improved ball in entirety or as a whole, the same comprising a core or filling 1 of suitable material, preferably elastic in character, and also preferably spherical, said core or filling being of comparatively large diameter proportionate to the diameter of the completed ball, although the same may vary in size, according to the predetermined depth or thickness of the outer shell 2 of the ball. The said outer shell preferably consists of alternating spherical laminæ of a substance 3, as celluloid, and a fibrous material 4, as permeable cloth of open mesh, substantially as shown, the said laminæ of celluloid or anal-

ogous substance being successively applied while in a soft or plastic condition by means of a brush or dauber or in any other suitable way. In some instances I make the exterior 5 surface of the outermost lamina of the outer shell preferably smooth or even; but to better adapt the ball to the purposes of the golf-game I preferably indent such surface or form the same of a brambled or pebbled character, 10 as indicated at 5, Fig. 1.

In forming the outer shell upon the core or filling 1 I first apply directly to the surface of the latter a soft or plastic lamina of the celluloid or analogous substance 3, to which 15 in turn I apply a lamina of the fibrous material 4, the said first-named lamina being then partially hardened or seasoned, preferably from without and either by artificial means or merely by ordinary cooling. I then apply 20 to said lamina of fibrous material another lamina of the celluloid substance in the same way, and so on, as already explained, after which the whole mass or structure is subjected to pressure in the heated finishing-dies 10 25 and 12, and while under such pressure parts of the celluloid laminae are forced into the interstices or meshes of the fibrous laminae. Thus the outer shell may be said to constitute spherical strata of intersecting veins of 30 different diameters, and a comparatively homogenous character is imparted to the entire shell due to a sort of interlocking engagement which takes place between the finely-divided portions of adjacent celluloid laminae, which are forced through the interstices or meshes of the cloth laminae from both directions, the effect of which is to prevent circumferential or lateral displacement of either 35 or the laminae of which the said outer shell of 40 the ball may be constituted. Variations of the structure of my improved ball may be adopted without departure from my invention.

Having described my invention, I claim—

1. The process herein described of making 45 playing-balls, which consists in applying in alternation laminae of plastic and fibrous materials to a suitable core, causing said plastic material to season or harden upon the ball, and finally completing the ball by compres- 50 sion.

2. The process herein described of making playing-balls, which consists in applying in

alternation laminae of plastic and fibrous materials to a suitable core, seasoning each of said plastic laminae before the next fibrous 55 lamina is applied, and finally compressing the structure.

3. A process in producing a playing-ball, consisting in coating a yielding core with celluloid solution, hardening said coating, and 60 applying thereto a lamina of fibrous material.

4. A process in producing a playing-ball, consisting in coating a yielding core with celluloid solution, hardening said coating, applying thereto a lamina of fibrous material, 65 subjecting the core thus formed to heat and compression, and maintaining the compression while the shell cools.

5. A process in producing a playing-ball, 70 consisting in applying to a previously-formed sphere a lamina of fibrous material coating said lamina with celluloid solution, hardening said coating, subjecting the ball thus formed to heat and compression, and maintaining the compression while the shell cools. 75

6. A process in producing a playing-ball, consisting in applying to a core in alternation laminae of fabric and laminae of material in a plastic condition, allowing each plastic lamina 80 to harden before applying the next lamina, and then compressing and heating the whole.

7. A process in producing a playing-ball, consisting in applying successive layers of celluloid alternating with fabric upon a core, 85 said celluloid being applied in plastic condition and hardened or seasoned upon the ball, and then subjecting said layers to simultaneous pressure and heat, and maintaining the pressure until the celluloid hardens. 90

8. A process in making a playing-ball, consisting in applying to a core, a plurality of layers one after another of fluid or plastic material, hardening one layer before another is applied, alternating said layers with laminae 95 of fabric, subjecting the whole to heat and compression, and maintaining the compression while the shell cools.

ELEAZER KEMPSHALL.
